UNITED STATES PATENT OFFICE

141,832

DESIGN FOR AN ELECTRON MICROSCOPE

Robert Holley, Penfield Downs, Pa., assignor to
Radio Corporation of America, a corporation of
Delaware

Application May 26, 1944, Serial No. 113,765

Term of patent 14 years

(Cl. D26—5)

To all whom it may concern:

Be it known that I, Robert Holley, a citizen of the United States and a resident of Penfield Downs, in the county of Delaware and the State of Pennsylvania, have invented a new, original, and ornamental Design for Electron Microscopes, of which the following is a specification, reference being had to the accompanying drawing, forming a part thereof.

The drawing is a view in perspective of an electron microscope showing by new design.

The back is plain and the side which is not shown is a substantial duplicate of the one which is shown.

I claim:

The ornamental design for an electron microscope, substantially as shown and described.

ROBERT HOLLEY.
